United States Patent Office.

CALVIN D. SMITH, OF BALDWINSVILLE, MASSACHUSETTS.

Letters Patent No. 77,116, dated April 21, 1868.

IMPROVED TILTING CHAIR.

The Schedule referred to in these Letters Patent and making part of the same.

TO ALL PERSONS TO WHOM THESE PRESENTS MAY COME:

Be it known that I, CALVIN D. SMITH, of Baldwinsville, in the county of Worcester, and State of Massachusetts, have invented a new and useful or improved Tilting Chair; and do hereby declare the same to be fully described in the following specification, and represented in the accompanying drawings, of which—

Figure 1 is a side elevation,

Figure 2 a front view, and

Figure 3 a vertical section of it.

From the seat, *a*, and back, *b*, of the chair, projections *c c* extend downward, and embrace the opposite sides of a base-frame, *A*, which is designed to rest on the floor. Each of the parts *c c* is connected to the said frame *A* by means of a journal, *d'*, extended from the frame, and into the said part *c*, the same being to enable the chair to be tilted on such journals.

A roller or barrel, *d*, arranged between and having bearings in the cheeks *e e* of the frame *A* has two bands, *f g*, fixed to the lower part of its circumference, they being wound around the roller in opposite directions, and fastened, at or near their upper ends, to the seat of the chair.

In rear of the roller is a rod, *h*, which extends from one cheek to the other of the frame *A*, and serves to support one end of a bow-spring, *i*, which is fixed to it. This spring, arranged with respect to the roller, in manner as represented in fig. 3, is connected to the middle of the lower part of the roller, by means of a ring, *l*, and a link or loop, *m*.

The spring, by its arrangement, will operate, with the roller and the bands, to check the chair while being tilted in either direction.

By the mechanism applied to the chair and its supporting-stand, the chair may be moved or tilted with great ease by and to a sitter.

I claim the arrangement and combination of the spring, the bands, and the barrel or roller, as applied to the chair and its stand.

Also, their arrangement with and application to the stand and chair, substantially in manner as specified.
